PROTECTIVE DEVICE AND SIGNAL MEANS
FOR CIRCUIT BREAKERSAlwin G. Steinmayer, Milwaukee, Wis., assignor
to Line Material Company, Milwaukee, Wis., a
corporation of Delaware

Application May 19, 1944, Serial No. 536,335

10 Claims. (Cl. 177—311)

1

This invention relates to a switch construction.

In greater detail, this invention relates primarily to a switch construction of the circuit breaker type.

Objects of this invention are to provide a circuit breaker which has a quick make and a quick break, which has condition responsive means of the trip type, which is so constructed that it releases the circuit breaker so that the circuit breaker will open under predetermined conditions, and which is provided with a handle or other operating means for normally opening and closing the circuit breaker and for resetting the trip means, the trip means and the operating means being so related that the trip means will operate to release the circuit breaker irrespective of the position of the operating means and irrespective of any motion that the operating means may be executing at the time the trip means operates so that the trip means is trip free and will operate no matter whether the operating means is forcibly held in closed position or is being moved from one position to another.

Further objects are to provide a circuit breaker which is so constructed that the circuit breaker cannot be closed until the trip means has moved back to normal position, and in which the resetting of the trip means is accomplished by moving the operating means towards open position, such motion being followed by movement to closed position after the resetting of the trip means when it is desired to again close the circuit breaker after the occurrence of the predetermined condition.

Transformers are frequently mounted in relatively remote locations and are not frequently inspected. It occasionally happens that a transformer is either permanently overloaded or else overloaded at certain periods and yet no warning of this condition is given. This invention has for a further object to provide a novel form of circuit breaker which may be mounted in a transformer casing and which in addition to the means adapted to trip the circuit breaker when an overload occurs is also provided with means adapted to give an indication or signal that the transformer is overloaded, though this overload may be to an extent not sufficient to trip the circuit breaker, and which is so made that after the signal has been given, the signal will persist until the signal controlling means is reset so that it becomes an easy matter for a lineman to ascertain the condition of a transformer with-

2

out requiring him to conduct elaborate and extensive tests.

It is to be noted that frequently overloads occur which last through a prolonged period sufficient to heat the transformer to a material and undesirable degree and yet which are not sufficient to trip the circuit breaker. This invention, as stated hereinabove, provides means which will function independently of the circuit breaker tripping means and which means may be independently adjusted without changing the adjustment of the circuit breaker tripping means so that any desired spread between the response of the signal controlling means and the response of the circuit breaker tripping means may be secured, and to so construct the apparatus that the signal controlling means may be reset without opening the circuit breaker, and which is also so made that the circuit breaker cannot be reset without resetting the signal controlling means.

In greater detail, objects of this invention are to provide a circuit breaker adapted to be mounted within a transformer casing and provided with two distinctly separate thermostatically responsive means, one of which is adapted to trip the circuit breaker and the other of which is adapted to cause the closing of a signal switch, such, for example, as a light switch, and in which readily accessible means are provided for independently setting the adjustment of the thermostatic means for tripping the circuit breaker and the thermostatic means for closing the signal switch.

Further objects are to provide a circuit breaker construction which, as stated, may be installed within a transformer casing and may be mounted above or submerged in the oil in the transformer casing, as desired, and which may be arranged so that one or both of the thermostatic means responds solely to the heat generated by the current passing through the thermostatic means or to the combined action of the heat of the oil from the transformer as well as the heat due to current passing through the thermostatic means or which may be arranged to respond solely to the heat of the oil.

Further objects are to provide a circuit breaker which has a heavy contact pressure when it is closed, in which this heavy contact pressure is maintained during the operation of the circuit breaker until the instant at which the contacts are suddenly separated, thereby avoiding burning of the contacts under overload conditions.

Further objects are to provide a circuit breaker in which the trip means is required to exert only

a very small force in order to cause automatic operation, the relation of the parts insuring retatching without any chance of wedging or jamming either the trip mechanism as a whole or any portion of the latch means.

Embodiments of the invention are shown in the accompanying drawings, in which:

Figure 1 is a sectional elevation of the circuit breaker, such view corresponding to a section on the line 1—1 of Figure 2, and showing the circuit breaker in closed position.

Figure 2 is a sectional view on the line 2—2 of Figure 1 and on the line 2—2 of Figure 3.

Figure 3 is a sectional view on the line 3—3 of Figure 2.

Figure 4 is a sectional view on the line 4—4 of Figure 3.

Figure 5 is a sectional view on the line 5—5 of Figure 3.

Figure 6 is a sectional view corresponding to Figure 3 with some of the parts shown in full, such view showing the circuit breaker in manually open position.

Figure 7 is a view corresponding to Figure 3 showing some of the parts in full and showing the circuit breaker in automatically tripped position.

Figure 8 is a top plan view with the cover removed and with parts broken away.

Figure 9 is a fragmentary view showing the circuit breaker mounted in a transformer casing.

Figure 10 is a view taken on line 10—10 of Figure 9.

Figure 11 shows the circuit breaker positioned in a casing for wall mounting.

Figure 12 is a wiring diagram.

The circuit breaker comprises a base portion 1 formed of insulating material and provided with a raised, centrally located portion 2 which has an upwardly extending, integral projecting part or stop member 3. A top portion 4 is also formed of insulating material and is spaced upwardly from the base portion. The top is provided with a pair of downwardly extending integral leg portions 5 which fit within recesses 6 formed in the base. The legs 5 are joined by an integral transverse web or bar 7. A cover 8 is provided above the top portion 4 and is suitably seated in a flanged marginal portion of the top 4 as shown. A metal casing or housing 9 is positioned between the top and bottom portions and is seated in grooves formed in such portions. The cover, top and bottom portions are held together by means of a pair of front tie rods 10 and a rear tie rod 11.

It will be seen that the construction provides a relatively large housed portion between the base 1 and the top 4 within which substantially all of the operating mechanism is positioned and that the space between the cover 8 and the top 4 provides a housed spaced within which the thermostatic members or condition responsive means is positioned.

The circuit breaker chosen for illustration is a two pole circuit breaker provided with a pair of stationary contacts 12 which are connected to the line terminals 13. The movable contacts are indicated at 14 and are in the form of plug-shaped members secured to rigid arms 15, see Figure 1. The movable contacts are each carried by a channel-shaped metal member 16 and are freely slideable through the rear wall of such member. Each movable contact 14 is urged outwardly by a spring 17. The metal channel-shaped members 16 loosely house the rigid arms 15. The metal channel members 16 are rigidly secured to a rock

shaft indicated generally at 18. This rock shaft, as shown most clearly in Figure 3, is provided with a rectangular metal center member 19 which is encased in a rectangular insulating sheath 20. The rigid arms 15 are connected to flexible leads or conductors 21 which extend upwardly on opposite sides of the device and are connected to connecting portions 22 in turn electrically connected to the right and left-hand pair of thermostatic members, as may be seen from Figures 1 and 8.

Each pair of thermostatic means comprises an outer thermostatic member 23 adapted to control a light switch and an inner thermostatic member 24 adapted to control the circuit breaker. These thermostatic members are bimetal members and will be described in greater detail hereinafter. The thermostatic members 23 and 24 are individually anchored at their rear ends and adjacent their free ends are electrically joined by means of flexible connectors 25 to the load terminals 26, see Figure 8. This permits independent mechanical motion of the thermostatic members 23 and 24 although such members are electrically connected. The purpose of this will appear hereinafter.

Switch operating means in the form of a channel-shaped metal member 27 is rigidly secured to the shaft 18, as shown in Figures 3, 6 and 7. The switch operating means 27 is provided with elongated, longitudinally extending slots 28 in its side walls within which flanged rollers 29 are adapted to travel. The rollers 29 are carried by a transverse shaft 30. The shaft 30 is carried by an actuator formed of a pair of members 31 which are pivoted as indicated at 32 to a rigid channel-shaped frame 33. The frame 33 is carried by the transverse web 7. The rollers 29 and the shaft 30 constitute the first pivot means and are adapted to rock the switch to open and closed position when the actuator is rocked about the pivot pins 32 in a manner hereinafter to appear.

The upper end of the switch operating means 27 has spaced arms which are provided with a second pivot means which consists of shafts 34 upon which rollers 35 are mounted, see Figures 1, 4 and 7. The rollers 35 are adapted to travel in arcuate slots 36 formed in the rigid frame 33 and the shaft and rollers constitute the second pivot means for the switch operating member 27. Normally the second pivot means is held locked in its outermost position, that is to say, adjacent the righthand end of the slot 36 as viewed in Figure 1, by means of the main latch lever 37. This latch lever is provided with a pair of arms located on opposite sides of the rigid frame 33 and pivoted as indicated at 38 to such frame. The arms are joined by means of a transverse web 39 provided with cut out portions 60 40, see Figure 4.

Biassing means are provided which bias the second pivot means 34, 35 to the left as viewed in Figures 4 and 7. This biassing means consists of a compression spring 41 which bears at opposite ends against U-shaped bail like members 42 and 43. The bail like member 42 is loosely pivoted on the pins 38 and the bail like member 43 is loosely pivoted on the pins 34. A flat bar 44 extends loosely through the spring 41 and 70 through the bail member 43 and is secured to the bail member 42. However, as stated the second pivot means 34, 35 is prevented from moving to the left under normal conditions by means of the latch lever 37. Each of the arms of the 75 latch lever is provided with a downwardly pro-

jecting portion 45, see Figure 1, which is provided with a face 46 which has a slight slant, as may be seen from Figure 1 so that it acts like a cam and tends to bias the latch lever 37 towards clockwise or unlatching motion. It is also to be noted that the latch lever, due to the fact that its right-hand portion is heavier than its left-hand portion, is also biased toward clockwise motion by means of gravity.

The latch lever is normally prevented from moving to releasing position by means of a latch bar 47 pivoted intermediate its ends by means of the headed screw member 48 to the web 39 of the latch lever, as shown most clearly in Figure 2. The latch bar 47 is provided with a pair of outwardly projecting end portions 49 which are engaged by downwardly projecting fingers 50 of a spring 51 loosely coiled about the member 48.

The parts are so arranged, as may be seen from Figures 2, 3 and 4, that the fingers 50 bear against the front face of the web 39 of the main latch lever and thus normally hold the latch bar 47 in a definite predetermined position transversely of the main latch lever 37. Auxiliary latch members 52 are loosely mounted on a pivot pin 53 and are preferably rigid with sleeves 53', see Figure 2, to provide adequate bearing surface on the pin. The auxiliary latch members 52 are provided with flat faces 54 which normally engage beneath the projecting portions 49 of the latch bar, see Figure 3. These auxiliary latches or latch members 52 are urged in a counterclockwise direction by means of springs 55. They are normally prevented from rotation by means of shouldered portions 56 formed thereon and respectively engaging circular pads or members 57 rigid with threaded stems 58, which stems are threaded through insulating blocks 59 rigidly carried by the outer or free ends of the inner thermostatic members 24. Adjusting knobs 60 are carried by each of the threaded stems 58 but are not threaded thereon. Nuts 61 and washers 62 are also carried by the threaded stems 58 and springs 63 bear against the nuts and against washers 64 which in turn rest upon fittings 65 carried by the insulating blocks 59, see Figure 3. The fittings 65 are each provided with an upturned finger 66 which is adapted to be engaged by the upturned finger 67 to thereby limit the extent of rotation of the adjusting knob 60.

It is to be noted that bimetal thermostatic members vary due to differences in material and in the process followed in their manufacture. Wide variations are taken care of by properly adjusting the threaded stems 58, it being noted that the upper end of the stems are slotted to receive a screw driver. After proper adjustment has been obtained, the knobs 60 are soldered or otherwise secured to the threaded shanks 58. Thereafter a certain range of adjustment is permitted as the knobs 60 may be rotated approximately a full revolution. In other words, the range through which the thermostatic members are to work is determined by the rough adjustment of the stems 58 in the insulating members 59 by means of a screw driver, as previously described, and within this range the exact adjustment at which the thermostatic members are adapted to release the trip means is determined by the adjustment of the knobs 60.

The pins 53 may be carried by upturned arms 68 integral with a plate 69 secured to the top portion 4. The plate 69 is provided with projecting fingers 70 which are adapted to be engaged by the extensions 71 of the auxiliary latches

52 to thus limit their counterclockwise motion. It is to be noted that each of the auxiliary latches 52 is provided with a cam like extension or finger 72. The purpose of these fingers 72 will be apparent when the operation of one of the thermostatic members 24 is considered. Suppose, for example, that one of the thermostatic members 24 operates and releases its auxiliary latch 52. This latch will execute a counterclockwise motion and in so doing the fingers 72 will strike the corresponding finger 49 of the latch bar and will rock the latch bar and cause disengagement of the other end of the latch bar from the other auxiliary latch 52, thus releasing the main latch lever 37. If both thermostatic members 24 release their auxiliary latches 52 simultaneously, it will be seen that both auxiliary latches move away from the transversely extending latch bar and disengage the respective ends 49 thereof and allow the main latch lever 37 to move to releasing position.

The automatic release on overload is apparent from the above described structure. For example, when one or both of the thermostatic members or condition responsive members 24 releases its corresponding auxiliary latch lever 52, the main latch lever 37 will rock in a clockwise direction due to the fact that it is biased by gravity towards this motion as its right-hand end is considerably longer than its left-hand end. However, it is more heavily biased towards this releasing motion due to the fact that the latching face 46, see Figure 1, is in reality a cam face and the pressure of the second pivot means 34, 35 against such face tends to cause clockwise or releasing rocking motion of the main latch lever 37. When the main latch lever 37 releases the second pivot means 34, 35, the switch operating means 27 pivots about the first pivot means 29, 30 as it is biased towards counterclockwise motion by means of the spring 41 and the switch operating means and movable contacts 14 move from the position shown in Figures 1 and 3 to the position shown in Figure 7.

45 Main operating means are provided for operating the switch and for resetting the automatic tripping means. This main operating means comprises a U-shaped, bail like member 73 which is pivoted as indicated at 74 on opposite sides of 50 the stationary frame 33. The main operating member 73 may be rocked from the position shown in Figures 1 and 3 to that shown in Figure 6 in any suitable manner, as by means of connecting links 75 pivotally connected by means of a transverse pin 76 with the main operating means 73 at their outer ends and at their inner ends pivoted to a crank 77 rigidly mounted on a transverse rock shaft 78 carried in suitable supports and extending laterally through one side of the housing 9 as shown in Figure 5.

65 The rock shaft 78 may be operated in any suitable manner as by means of a handle 79 located externally of a transformer casing 80, the circuit breaker being preferably carried by the transformer indicated generally by the reference character 81 and mounted below the level 82 of the oil within the casing, see Figure 9. Obviously the rock shaft 78 could be operated in any other manner desired, as by means of cranks and link mechanism from a rock shaft mounted above the oil level if desired. If the outwardly projecting extension 83 of the rock shaft is below the oil level 82, a suitable packing is provided to prevent loss of oil.

70 The main operating means 73 is connected by

means of a pair of springs 84 with the first pivot means 29, 30. Preferably fittings 85 and 86 are provided for the outer ends of the springs 84. These fittings are seated within grooves formed in the pins or shafts 78 and 80, see Figure 3. The fitting 85 is mounted between the flanged rollers 28. It is also preferable to provide collars 88 on the shaft 78 to prevent shifting of such main operating shaft.

The main operating member 73 is provided with pins 89 which project inwardly from opposite sides and which are adapted to operate within slots 90 formed in opposite sides of the frame 33. These pins project into cut out portions 91 in the actuator formed of the members 31. It is to be noted that the cut out portions 91 in the actuators 31 are so shaped that shoulders 92 are provided, see Figure 3. The purpose of these shoulders will appear from the following description of the manual operation of the apparatus.

Assume that the circuit breaker is in closed position and it is desired to manually open it. This is accomplished by rocking the rock shaft 78 and thereby moving the main operating means 73 from the position shown in Figures 1 and 3 to the position shown in Figure 6. During this rocking motion the line of pull of the springs 84 will pass across the pivot means 32 of the actuator composed of the members 31 and will cause the actuator to suddenly rock in a clockwise direction to the position shown in Figure 6, thereby suddenly opening the circuit breaker. Obviously closing motion is accomplished by moving the main operating means from the position shown in Figure 6 to the position shown in Figure 3, the closing motion of the circuit breaker being very quick in view of the fact that the line of pull of the springs again crosses the pivot 32 of the actuator in passing from the position shown in Figure 6 to that shown in Figure 3. The shoulders 92 on the members 31 constituting the actuator, see Figure 3, have a double function. One of the functions is to start motion of the actuator at approximately the instant that the line of pull of the springs 84 is crossing the pivot point of the actuator when the main operating means 73 is being moved from the position shown in Figure 3 to that shown in Figure 6. The other purpose of the shoulders 92 is to insure opening of the circuit breaker by positive engagement between the pins 89 and the shoulders 92 even through the springs 84 should break, thus providing this additional safety feature.

The resetting after automatic tripping is accomplished by moving the main operating means 73 from the position shown in Figure 7 to the position shown in Figure 6. Prior to the time that the main operating means 73 arrives at the position shown in Figure 6, it will be noted that the line of pull of the springs 84 passes across the pivot point of the actuator and consequently pulls the upper end of the switch operating means 27 to the right as viewed in Figure 6, thus compressing the spring 41 as the springs 84 exert a greater force than the spring 41. It is to be noted that the projecting portion 3 which extends upwardly from the base 1 is engaged by the transverse insulated shaft 18 of the switch operating means 27 during this resetting operation and consequently the switch operating means 27 pivots about the point of engagement between the shaft 18 and the projection 3. As the main operating means 73 continues upwardly to the position shown in Figure 6, it will engage the downwardly projecting portions 93 of the main

latch lever 37 and will rock such main latch lever to the position shown in Figure 6, the second pivot means 34, 35 having been first positioned to the right of the hook-shaped left-hand end of the main latching lever 37.

It is to be noted also that the auxiliary latches 52 are also reset. If both of the auxiliary latch levers 52 have been released by simultaneous action of the thermostatic members 24, it will be noted that the latch bar 47 will move upwardly and will simultaneously engage the cam portions 72 of each of the auxiliary latch levers 52 and will rock such latch levers to the position shown in Figure 6. During this motion, assuming that the thermostatic members 24 have cooled, the cam like portion 84 of the auxiliary levers will ride beneath the stops or pads 51 and will slightly raise the pads until the latching faces 56 of the auxiliary latch levers 52 are to the right as viewed in Figure 6 of the members 51. Thereafter when the main operating means 73 is moved downwardly towards closed position from the position shown in Figure 6, the transverse latch bar will rest upon the flat portions 54 or hook portions 54 of the auxiliary latch levers 52.

If only one of the thermostatic members 24 had operated, its auxiliary latch lever 52 would be released but the other latch lever would still be held by its thermostatic member 24. Under these conditions when the main latch lever 37 is rocked from the position shown in Figure 7 to that shown in Figure 6 during resetting, the appropriate end 49 of the latch bar will first engage the cam portion 72 of the released auxiliary latch lever 52 and its opposite end 49 will be rocked inwardly and will thus clear the hook portion of the unreleased auxiliary latch member 52. Continued upward motion of the latch lever 37 will cause the latch bar 47 to reset the released auxiliary latch lever 52 as the cam portion 72 of the unreleased auxiliary latch lever 52 will rock the latch bar 47 by engaging one end 49 thereof and cause the other end 49 to rock inwardly and reset the released auxiliary latch lever 52.

A pair of signal switch members are provided and are connected together. Each signal switch member comprises a stationary contact member 95 and a movable contact member 96 normally spring urged towards open position as shown in Figure 1. These signal switches are connected in parallel as is obvious and in series with a signal lamp or other signal means indicated by the reference character 97 in Figures 9 and 12. This signal lamp may be supplied from either secondary winding 98 of the transformer 99, see Figure 12, or may be, in the preferred form, supplied from a separate secondary 100 of the transformer 99. The signal switch means are controlled by the outer thermostatic member 23, see Figures 1 and 8. These thermostatic members are provided with insulating blocks 101 at their free ends through which threaded stems 102 pass. These stems are provided with pads or stop members 103 and with adjusting knobs 104 of identically the same construction as those previously described and initially set and subsequently accurately adjusted in exactly the same manner as that previously described.

Each thermostatic member 23 controls a signal switch operating means 105 which is mounted opposite the movable contact 96 of the signal switch and which is urged by means of a spring 106 in a counterclockwise direction towards sig-

nal switch closing motion. It is normally restrained by the engagement of the shoulder 107 of the signal switch operating means 105 with the stop or pad 103 of the thermostatic member. When the thermostatic member releases the signal switch operating means 105, such signal switch operating means closes its signal switch. The signal switch operating means 105 is provided with a cam face 108 so that the cam face will ride beneath and raise the pad or stop 103 when the signal switch operating means 105 is reset.

Each signal switch operating means 105 is pivotally mounted upon a fixedly positioned pin 109 carried by the stationary arms of a bracket 110 secured to the top 4. Preferably sleeves 109' have their ends riveted to the members 105 to provide extensive bearing surfaces on the pins 109. The signal switch operating means 105 are provided with projecting pins 111 which are adapted to be engaged by the upper ends of resetting levers 112 pivotally supported on the shaft 113 which in turn is supported from the base 1, see Figures 1 and 2. Preferably tubular members or sleeves 114 are riveted as indicated at 115 to the resetting levers 112 so as to provide the resetting levers with elongated bearings which are supported by the shaft 113.

The levers 112 are provided with cam portions 116 adapted to be engaged by the transverse pin 76 of the main operating means 73 when such main operating means is rocked upwardly. The cam portions 116 of the resetting levers 112 are so positioned that resetting takes place when the main operating means 73 is moved towards switch open position but prior to the opening of the circuit breaker so that it is possible, if it becomes desirable, to open the signal switch means by resetting the signal switch operating means without opening the circuit breaker.

The adjustment of the threaded stems 58 and 102, see Figures 1 and 3, which are supported from the thermostatic members 24 and 23 respectively, is such that any desired spread between current values required to operate the respective thermostatic members may be obtained so that the signal switch means will be closed for a current value and time interval less than that for which the circuit breaker will be opened.

The circuit breaker may be adapted for wall mounting as indicated in Figure 11 and may be completely housed as indicated at 9' and may be provided with an external lever or arm 79' for operating such circuit breaker. The signal lamp or other signal means, not shown in Figure 11, may be mounted either on the casing of the circuit breaker or at any desired point.

Referring to the wiring diagram of Figure 12, it will be seen that the primary of the transformer is indicated by the reference character 117 and that the secondary has a grounded neutral in the particular form chosen for illustration. It is obvious that either a single pole circuit breaker could be used where a single secondary is employed or a two pole circuit breaker could be used for the three wire grounded neutral system shown in Figure 12, or any number of poles could be provided by suitably extending the shaft 18, see Figure 1, and providing it with the necessary number of movable contacts 14 and providing a corresponding number of stationary contacts 12.

It will be seen that a novel form of circuit breaker has been provided which is so made that it may be mounted in the casing of a transformer or other instrumentality and is arranged

to give an indication of an overload and which is also arranged to open the circuit in the event the overload reaches a predetermined value. The invention is particularly useful in that it will indicate an overload of any predetermined magnitude which may be of a lesser value, for example, than that required to open the circuit breaker but which nevertheless may be of such a value as to cause undue heating of the transformer. It is obvious, therefore, that the indicating means may be set to respond to an overload of a predetermined value and the circuit breaker opening means may be set to respond to an overload of a greater value and any desired spread or difference in current values for these two operations may be obtained by appropriate adjustment of the device.

It is to be noted further that when the signal switch means is once closed, it remains closed until manually opened, as described hereinabove. In this manner an indication is given of the fact that the transformer either is continuously overloaded or has been overloaded at some period between inspections. Thus the lineman is apprised of the condition of the transformer by a casual inspection thereof without requiring any elaborate tests. It is therefore possible to determine whether the transformer is adequate for the load normally carried thereby and also possible to determine whether the peak load at any particular time in the day exceeds the rated capacity of the transformer by suitably timing the inspection of the signal light. For instance, if it is believed that an overload occurs only between certain hours, it is possible by attempting to reset the signal means and observing it during these hours and at other times to determine just when the overload occurs. It is obvious that if the overload still persists at the time an attempt is made to reset the signal means, that the thermostatic member or members controlling the signal light will be in a position to prevent resetting as they will be out of position to hold the signal light controlling means in signal switch open position. On the other hand, if the overload has ceased at the time it is attempted to reset the signal means, the signal means will of course remain in non-signalling position when the signal means is reset. The ability to reset the signal means without opening the circuit breaker is a material asset for the apparatus as it enables tests of the above described type to be conducted without disturbing the service to the customers.

In this connection it is to be noted particularly that separate and independent condition responsive means, such as the bimetallic thermostatic members, are provided for respectively controlling the signal means and the circuit breaker release or opening means and that these two instrumentalities may be independently adjusted in a very easy and simple manner, each condition responsive means being wholly independent in its action from the other.

It is to be noted further that the adjustment of the thermostatic release means is very accurate and the exact value at which each thermostatic means will respond can be accurately predetermined by the adjustment of the adjusting knobs. If desired, it is obvious that scales, not shown, could be provided to indicate the values of current at which the respective thermostatic members will respond. By having the thermostatic members controlling the signal means and the circuit breaker wholly distinct and sepa-

11

rate as discussed hereinabove, a wide range of adjustment is permitted as the motion of each thermostatic means is wholly independent of the motion of the other thermostatic means and therefore the adjustment of the two thermostatic means is obtained without any thought on the part of the operator as to a change that would have been produced in the other thermostatic means had they been mutually dependent one on the other.

It is to be noted that the first or main overload responsive means or thermostatic means 24 in conjunction with the main switch means protects the second overload responsive means or thermostatic means 23 by opening the circuit if the overload exceeds a predetermined value. This is very desirable as the second overload means or thermostatic means 23 responds to a lesser overload and would become injured on very much larger overloads unless the main or first overload responsive means or thermostatic means would cause the main switch to open.

Although this invention has been described in considerable detail, it is to be understood that such description is intended as illustrative rather than limiting, as the invention may be variously embodied and is to be interpreted as claimed.

I claim:

1. A circuit breaker formed as a unitary structure and comprising switch means, switch operating means for opening and closing said switch means, main operating means for operating said switch operating means, biased means for moving said switch operating means towards switch open position, a first condition responsive means normally restraining said biased means and releasing said biased means upon the occurrence of a predetermined condition, a second condition responsive means distinct and separate from said first condition responsive means and operable independently of said first mentioned condition responsive means, said second condition responsive means being responsive to a condition of lesser magnitude than said first condition responsive means, signal means controlled from said second condition responsive means and actuated upon the occurrence of a second predetermined condition, said signal means normally occupying a non-signalling position and being movable upon the occurrence of said second condition to a signalling position, and means actuated from said main operating means for restoring said second means to its non-signalling position.

2. A circuit breaker comprising switch means, switch operating means for opening and closing said switch means, main operating means for operating said switch operating means, biased means for moving said switch operating means towards switch open position, a first condition responsive means normally restraining said biased means and releasing said biased means upon the occurrence of a predetermined condition, a second condition responsive means, said second condition responsive means being responsive to a condition of lesser magnitude than said first condition responsive means, signal means normally occupying a non-signalling position and controlled from said second condition responsive means and movable to a signalling position upon the occurrence of a second predetermined condition, said signal means remaining in signalling position, and means actuated from said main operating means for restoring said signal means to its non-signalling position.

3. A circuit breaker comprising switch means,

12

switch operating means for opening and closing said switch means, main operating means for operating said switch operating means, biased means for moving said switch operating means towards switch open position, a first condition responsive means normally restraining said biased means and releasing said biased means upon the occurrence of a predetermined condition, a second condition responsive means, said second condition responsive means being responsive to a condition of lesser magnitude than said first condition responsive means, signal means normally occupying a non-signalling position and controlled from said second condition responsive means and movable to a signalling position upon the occurrence of a second predetermined condition, said signal means remaining in signalling position, and means actuated from said main operating means for restoring said signal means to its non-signalling position when said main operating means is moved towards switch opening position.

4. A circuit breaker comprising switch means, switch operating means for opening and closing said switch means, main operating means for operating said switch operating means, biased means for moving said switch operating means towards switch open position, a first condition responsive means normally restraining said biased means and releasing said biased means upon the occurrence of a predetermined condition, a second condition responsive means, said second condition responsive means being responsive to a condition of lesser magnitude than said first condition responsive means, said first and second condition responsive means being adjustable each independently of the other, normally open signal switch means, signal switch operating means for closing said signal switch means and biased towards signal switch closing motion and normally restrained by said second condition responsive means and released upon the occurrence of a second predetermined condition, and means actuated from said main operating means for restoring said signal switch operating means to signal switch open position.

5. A circuit breaker comprising switch means, switch operating means for opening and closing said switch means, main operating means for operating said switch operating means to open said switch means when said main operating means is moved in one direction and to close said switch means when said main operating means is moved in the other direction, biased means for moving said switch operating means towards switch open position, a first condition responsive means normally restraining said biased means and releasing said biased means upon the occurrence of a predetermined condition, a second condition responsive means, said second condition responsive means being responsive to a condition of lesser magnitude than said first condition responsive means, said first and second condition responsive means being adjustable each independently of the other, a normally open signal switch, signal switch operating means biased towards signal switch closed position and normally restrained by said second condition responsive means and released upon the occurrence of a second predetermined condition, and means for restoring said signal switch operating means to its initial position when said main operating means is moved part way towards switch open position, whereby said signal switch means may be opened without opening said switch means

6. A circuit breaker comprising main switch means, main operating means including manually operable means for moving said main switch means to open and closed position, signal switch means, a first overload means responsive to a predetermined overload to cause closing of said signal switch means, means operated from said main operating means for moving said signal switch means to open position, and a second overload means distinct and separate from said first overload means and responsive to a different predetermined overload to cause opening of said main switch means, said first and second overload means being electrically connected and independently mechanically movable.

7. In a circuit breaker constructed as a unitary device and having main switch means, a signal switch means, a pair of biased elements for respectively causing opening of said main switch means and closing of said signal switch means, independent and separate means responsive to different predetermined conditions for selectively causing release of said biased elements, and main operating means for opening and closing said main switch means and for resetting said biased elements.

8. A circuit breaker comprising main switch means, main operating means including manually operable means for moving said main switch means to open and closed position, signal switch means, a first thermostatic means responsive to an electrical overload to cause closing of said signal switch means, means operated from said main operating means for moving said signal switch means to open position, and a second thermostatic means responsive to an electrical overload of a larger value than said first mentioned overload for causing opening of said main switch means, said first and second thermostatic means being electrically connected and being independently mechanically movable.

9. A circuit breaker comprising main switch means, main operating means including manually operable means for moving said main switch

means to open and closed position, signal switch means, a first thermostatic means responsive to an electrical overload to cause closing of said signal switch means, means operated from said main operating means for moving said signal switch means to open position, and a second thermostatic means responsive to an electrical overload of a larger value than said first mentioned overload for causing opening of said main switch means, said first and second thermostatic means being electrically connected in parallel and being independently mechanically movable.

10. A circuit breaker comprising main switch means, main operating means including manually operable means for moving said main switch means to open and closed position, signal switch means, a first thermostatic means responsive to an electrical overload to cause closing of said signal switch means, means operated from said main operating means for moving said signal switch means to open position, and a second thermostatic means responsive to an electrical overload of a larger value than said first mentioned overload for causing opening of said main switch means, said first and second thermostatic means being electrically connected and being independently mechanically movable, said first and second thermostatic means having independently adjustable means to selectively determine the overload at which said signal switch means will close and the overload at which said main switch means will open.
